UNITED STATES PATENT OFFICE

KENNETH E. BEMIS, OF GLENDALE, CALIFORNIA

LIQUID DISPENSER

Application filed July 14, 1931. Serial No. 550,722.

This invention is a liquid dispenser, which is particularly adapted to the dispensing of cream, syrups and other liquids in measured quantities.

5 The main object of the invention is to provide a liquid dispenser which provides accurately measured quantities so long as any liquid remains in the receptacle.

Another object of the invention is to provide 10 a device as outlined which is sanitary and readily cleaned and sterilized.

A further object of the invention is to provide 15 a device as outlined which is economically constructed and which will not readily get out of order.

Other objects and advantages of the invention will become apparent as the following description is read on the drawing forming a part of this specification and in which similar 20 reference characters are used to designate similar parts throughout the several views, of which

Fig. 1 is a sectional transverse elevation through the invention;

25 Fig. 2 is a front elevation, lower part in section, of the invention;

Fig. 3 is a section taken on line 3—3 of Fig. 1.

The invention consists of a container 10, 30 the bottom 11 of which is intermediately disposed and from which a well 12 is formed, the bottom 11 sloping from all directions to drain into the well 12. A cover 13 has an aperture provided at 14 in alignment with the well 12, 35 to slidably receive the skipway 15.

The skipway 15 consists of a rectangular tubular element slidably fitting into the well 12 and through the aperture 14. A slot 16 formed in the rear wall permits draining of 40 excess liquid from the skip 17. An opening 18 having inwardly extending lips 19 and an outwardly extending lip 20 causes the skip 17 to empty its measured quantity of liquid beyond the front face of the container 10, the 45 lips 19 dumping the skip and preventing withdrawal through the top.

The skip 17 has a semi-circular bottom 21 to permit its tipping, as shown in dotted lines at 22, and has an extended lip 23 to 50 carry the liquid clear of the skipway 15. An

opening 24 in the rear wall of the skip permits draining of excess liquid and the skip is pivotally suspended by means of a yoke 25, as indicated at 26. The yoke 25 is secured to a rod 27 which is slidable in a hole 28 formed in the top member 29 of the skipway 15. A knob 30 is threadedly secured at the upper end of the rod 27. A shield 31 extends over the opening 18 when in closed position and is detachably secured between a shoulder at 32 the top or rod 27 and the knob 30.

The invention is used as follows. The skip 17 has the opening 24 cut to a point where the lower portion will hold the required amount of liquid. The container 10 is filled with the liquid to be dispensed. By drawing upwardly on knob 30, the skip is lifted from the well 12, guided by the skipway 15, draining the excess over the edge 31 of the skip as it is raised above the liquid level. As the lip 23 strikes the lips 19, the skip 17 is tipped outwardly as shown by the dotted lines. As the knob is drawn upward, the cover 31 is raised with it as shown in Fig. 2, uncovering the opening 18. After 75 the liquid is emptied from the skip, the skip and cover return by gravity to the position shown in Fig. 1.

Having described an operative method of constructing and using the device it will be understood that variations in construction and arrangement of parts which are consistent with the appended claims may be resorted to without detracting from the spirit or scope of the invention or sacrificing any 85 of the advantages thereof.

I claim:

1. A dispensing device for liquids comprising a container having a skip well, a skipway of rectangular cross-section removably fitting in said well and extending upwardly above said container, a skip slidable in said skipway and provided with an upwardly extending lip and arcuate bottom, a lifter rod pivotally secured to said skip, a cover secured to said lifter rod, an aperture formed through the front of said skipway above said container and normally closed by said cover and an inwardly projecting lip at the upper end of said aperture adapted to cooperate 100

with the lip on said skip for dumping said skip, said lip forming a spout when projected through said aperture.

2. A liquid dispensing device, in combination with a container, a rectangular skipway, a skip slidable in said skipway and having an upwardly extending lip and arcuate bottom, a lifter rod pivotally secured to said skip, a cover secured to said lifter rod, an aperture formed in said skipway and having an inwardly projecting lip adapted to cooperate with the lip on said skip for dumping said skip when said skip is raised, said cover normally covering said aperture.
- 15 3. Skip dumping means for a liquid dispensing device comprising in combination with a skip having an upwardly extending lip, and lifting means for said skip, a skipway having an opening in the front wall thereof; an inwardly projecting lip at the upper edge of said opening adapted to cooperate with the lip on said skip whereby said skip is deflected through said opening forming a spout when said skip is raised and a cover for said opening fixedly secured to said lifting means.

In testimony whereof I have affixed my signature.

KENNETH E. BEMIS.
